LOCKING DEVICE

David Hart Hoffman, New York, N. Y.

Application October 28, 1941, Serial No. 416,797

2 Claims. (Cl. 151—25)

This invention relates to lock nuts and refers more particularly to locking devices which may be applied to nuts and the like to prevent the loosening thereof.

An object of the present invention is the provision of a lock nut which is simple in construction, inexpensive to manufacture and greatly effective in operation.

Another object is the provision of a locking device which may be conveniently applied to nuts of standard form and size for the purpose of locking the bolts carrying such nuts.

A further object is the provision of locking means which may be easily and effectively employed for preventing the turning of nuts or bolts in either direction or in both directions.

Other objects of the present invention will become apparent in the course of the following specification.

In accomplishing the objects of the present invention it was found desirable to provide a cam having a knurled or fluted surface extending at a gradually increasing radial distance from the fulcrum of the cam and pressed by a spring against the bolt. The cam may be pivoted directly upon the nut, or it may be carried by a support which is mounted upon the nut. A stop is preferably provided close to that portion of the cam which has the smallest radial distance, in order to ensure that pressure upon the bolt is exerted by cam portions having gradually increasing radii.

The invention will appear more clearly from the following detailed description when taken in connection with the accompanying drawing showing, by way of example only, preferred embodiments of the inventive idea.

In the drawing:

Figure 1 is a top view of a nut provided with a locking device constructed in accordance with the principles of the present invention.

Figure 2 is a section along the line 2—2 of Figure 1, looking in the direction of the arrows.

Figure 3 is a bottom view of the nut shown in Figure 1.

Figure 4 is a side view of the nut and the locking device.

Figure 5 illustrates the locking device when it is removed from the nut.

Figure 6 is a section through a locking device of a somewhat different type.

Figure 7 is a top view of the device shown in Figure 6.

The drawing shows a nut 8 of the usual hexagonal form which is screwed upon a bolt 9.

The locking device illustrated in Figures 1 to 5 includes a support 10 having the form of a substantially flat metallic strip 11 provided with a bent U-shaped end portion 12 extending over a part of the strip 11, and another end portion 13 bent at right angles to the strip in the opposite direction to that in which the end portion 12 is bent. A central opening 14 is provided in the strip 11 for the passage of the bolt 9. The bent portion 13 of the support 10 is so located in relation to the opening 14 that it can engage one of the sides of the nut 8, thereby preventing any accidental turning of the locking device.

The locking element of the device consists of a cam 15 having a hole 16 for the pivot or fulcrum. The cam 15 has an outwardly curved knurled or fluted surface 17 with ribs and grooves extending substantially in the direction of the bolt 9. The surface 17 which is adapted to engage the bolt 9, extends inwardly from an edge 18 to an edge 19, so that the distance of the edge 18 from the center of the hole 16 is greater than the distance of the edge 19 from that center.

The edge of the opening 14 opposed to the cam 15 is made sharp to facilitate its engagement with the threads of the bolt 9.

The cam 15 is so disposed in relation to a bolt 9 that any attempt to turn the bolt 9 in one direction will cause the cam 15 to exert a steadily increasing pressure against the bolt 9. Consequently, the cam 15 is pressed against the bolt 9 in the direction of the arrow 20 shown in Figure 1, namely, the portion of the surface 17 which first engages the bolt 9 is located close to the edge 19, and the pressure upon the bolt 9 is exerted along the surface 17 in the direction from the edge 18 toward the edge 19. Obviously, the cam 15 must be so shaped that the edge 19 of the surface 17 is at approximately the same distance from the center of the hole 16 as the closest peripheral point of the hole 14, and that the radial distance of the surface 17 gradually increases in the direction from the edge 19 to the edge 18 to provide a firm and positive engagement between a bolt 9 extending through the hole 14 and a part of the surface 17.

In the device shown in Figures 1 to 5, the cam 15 is swingably mounted upon projections 21 and 22 which are pressed out of the support 10 and which fit into the hole 16 of the cam 15. The projection 21 is formed upon the portion 12 of the support 10 and is directed inwardly and toward the projection 22 which is situated oppo-

site the projection 21 and upon the portion 11 of the support 10.

A tongue 23 is pressed or cut out of the portion 12 of the support 10, thus leaving an opening 24 in the support. The tongue 23 is bent inwardly and then brought into engagement with the side surface 25 of the cam 15, so that the tongue 23 can serve as a spring which exerts pressure upon the cam 15 in the direction of the arrow 20.

It is apparent from the above that the cam 15 should press against the bolt 9 along the cam surface 17 in the direction from the edge 18 toward the edge 19, and not in the opposite direction. To prevent an incorrect location of the cam 15, a stop 26 is pressed out of the portion 12 of the support 10, thereby leaving a hole 27. The stop 26 extends inwardly and is located close to the cam surface 28, which is opposite the surface 25 and which terminates in the edge 19.

In order to lock the bolt 9 it is merely necessary to place the support 11 over the nut 8 with the edge portion 13 of the support 11 in engagement with a side surface of the nut 8, the bolt 9 extending through the opening 14 of the support 11; the cam 15 is turned either manually or by any suitable tool in the direction opposed to that of the arrow 20, thereby bending the tongue or spring 23, while the support 11 is being mounted to clear the opening 14 for the bolt 9. As soon as the cam 15 is released, the tongue or spring 23 will cause the cam surface 17 to engage the bolt 9. Thereafter, it will not be possible to turn the bolt in the direction of the arrow 20, since any such movement will tend to move the cam 15 in the direction of the arrow 20, thereby steadily increasing the pressure of the surface 17 against the bolt 9 due to the increasing radial distance of the surface 17.

In the illustrated arrangement in which the support 10 is placed upon the surface 30 of the nut 8, the bolt 9 may turn freely in the direction opposed to that of the arrow 20. If the support 10 is placed upon the opposite surface 31 of the nut 8, the cam 15 will permit the rotation of the bolt 9 in the direction of the arrow 20, while any rotation of the bolt 9 in the opposite direction will be prevented. In order to lock the bolt 9 completely and thus prevent it from rotating in both directions, one locking device should be placed upon the surface 30 of the nut 8 in the manner illustrated, while another similar locking device should be placed upon the opposite surface 31 of the nut 8.

A locking device preventing the rotation of the bolt 9 in both directions is illustrated in Figures 6 and 7. This device comprises a cam 40 which is similar in shape to the cam 15 and which is swingably mounted upon a pivot 41. The pivot 41 is firmly mounted upon one side of a nut 8. A spring 42 has one end which is

carried by the pivot 41, while the other end of the spring 42 is embedded in the cam 40. The spring 42 tends to press the cam 40 against the bolt 9 in the direction of the arrow 43. The movement of the cam 40 is limited by a stop 44 which is carried by the nut 8.

This construction is repeated upon the opposite side of the nut 8 which carries a cam 45 mounted upon a pivot 46 embedded in the nut 8. The cam 45 is pressed against the bolt 9 by a spring 47.

The pressure of two cams 40 and 45 against the bolt 9 prevents any turning of the bolt. In order to release the bolt 9, both cams must be moved away from it simultaneously.

It is apparent that the specific examples shown above have been given by way of illustration and not by way of limitation and that the structures above described are subject to wide variation and modification without departing from the scope or intent of the invention. All of such variations and modifications are to be included within the scope of the present invention.

What is claimed is:

1. A device for locking a bolt carrying a nut, said device comprising a support having a substantially flat portion having an opening formed therein for said bolt, a U-shaped end portion having two opposed projections formed therein and constituting a pivot, and another end portion bent away from said U-shaped end portion and adapted to engage an edge of said nut, and a cam swingably mounted upon said pivot, said cam comprising a side surface extending to a comparatively greater distance from the center of said pivot, another side surface extending to a comparatively smaller distance from said center, and a substantially uniformly outwardly curved fluted, bolt-engaging surface extending between said side surfaces; said support further comprising a bent portion engaging the first-mentioned side surface of the cam to press said bolt-engaging surface against said bolt, and another bent portion constituting a stop adapted to engage said other side surface of the cam.

2. A device for locking a bolt, said device comprising a support having an opening formed therein for said bolt, and comprising a U-shaped end portion, a pivot carried by said U-shaped end portion, and a cam swingably mounted upon said pivot, said cam comprising a side surface extending to a comparatively greater distance from the center of said pivot, another side surface extending to a comparatively smaller distance from said center, and a substantially uniformly outwardly curved fluted bolt-engaging surface extending between said side surfaces, and resilient means engaging the first-mentioned side surface of the cam to press said bolt-engaging surface against said bolt.

DAVID HART HOFFMAN.
